UNITED STATES PATENT OFFICE.

EUGENE MOREHOUSE, OF PROVIDENCE, RHODE ISLAND, ASSIGNOR TO B. A. BALLOU AND COMPANY, INC., OF PROVIDENCE, RHODE ISLAND, A CORPORATION OF RHODE ISLAND.

SAFETY-CATCH FOR PINS.

1,034,136.

Specification of Letters Patent. Patented July 30, 1912.

Application filed December 17, 1910. Serial No. 597,788.

To all whom it may concern:

Be it known that I, EUGENE MOREHOUSE, a citizen of the United States, and resident of Providence, in the county of Providence and State of Rhode Island, have invented 5 certain new and useful Improvements in Safety-Catches for Pins, of which the following is a specification.

This invention has reference to safety 10 catch members for pins, its object being to provide a special construction of keeper having recessed bearings closed at their outer ends for the reception of the guard trunnions, whereby an exceptionally strong and 15 durable keeper is obtained, and a further object of the invention is to so mount the guard in said keeper that the same is adapted to be rotated to close the mouth of the keeper and when closed to be retained in 20 that position by the pin-tongue under spring tension.

With these and other objects in view, the invention consists of certain novel features of construction, as will be more fully described and particularly pointed out in the appended claims.

In the accompanying drawings: Figure 1—is a side elevation of my improved safety catch retaining the point of an ordinary pin 30 stem, the opposite end of said stem being secured to the pin body by a joint in the usual way. Fig. 2—is an enlarged side elevation of the catch member showing the guard in position to open the mouth of the keeper. Fig. 3—is an enlarged side elevation of the 35 catch member showing the guard in position to close the mouth of the keeper. Fig. 4—is a detail showing the keeper as blanked out of sheet stock with the recess swaged and the pin-tongue receiving slots formed therein. Fig. 5—is a perspective view of the guard 40 member. Fig. 6—is a perspective view of one side of the keeper bent up into position, the opposite side being removed. Fig. 7— 45 represents both sides of the keeper being bent up over the trunnions on the guard to connect the whole together. Fig. 8—is a central sectional side elevation of the guard retained in the keeper showing the slot 50 through both for the reception of the pin stem.

Having reference to the drawings, 1 designates the usual pin stem mounted at one end in the joint member 2 attached to the body

portion 3. My improved safety catch member 4 may be formed integral with, or made 55 separate and attached to the opposite end of the pin body, to receive the pointed end of the pin stem, said catch being constructed of two members, one the keeper 5 and the 60 other the guard 12. In forming the keeper it is preferably blanked out of sheet stock 65 into the shape illustrated in Fig. 4 having a pair of enlarged ears or members 6—6 joined together by the connector 7, which connector 70 serves as a base when the ears are bent up into operative position. These ears, are centrally recessed at 8—8 the stock 9—9 being pressed from the inner side outward into a cup- 75 shape, but not punched way through forming a housing for receiving and completely inclosing the trunnions on the guard member hereinafter described. By this construction the full strength of the metal in the hook portion of these ears is retained, which 80 would not be the case if the recessed stock were entirely remove, thus permitting the keeper to be constructed from very thin, light stock which in practice is found very advantageous particularly when the catch is 85 made of the precious metals.

A slot 10 may be formed through the wall or walls of one or both of these ears, the same to extend from the margin thereof 85 preferably near the base portion upward or inward at an angle to said base and slightly beyond the center portion of the ears, said slot or slots being for the purpose of receiving the pointed end of the pin stem. That portion of said slot or slots which extends 90 beyond the center of the ears is preferably directed slightly upward or in a direction away from the base forming a locking recess 11 but I do not wish to restrict myself to extending this recess upward from the 95 center as it may extend in any direction into which the pin-tongue may follow by its own spring tension to form a lock when the guard is in its closed position.

The guard member 12 is constructed es- 100 sentially in a disk form having short laterally extending trunnions 13—13 and an operating handle 14 extending radially outward from its periphery. A radial slot 15, the bottom portion of which being design- 105 ated at 15^a is formed through the disk and trunnions from its margin inward to its center, said slot being in a position to regis-

ter with those in the keeper when the handle 14 is carried around against the stop 16 on the back of the keeper.

The construction and operation of the device may be further described as follows: The keeper and guard members are formed separately, the keeper is bent up first into the form illustrated in Fig. 7 and then into that illustrated in Fig. 8. The recesses 8, 10 (which are made in a cup form) receive and entirely inclose or house the trunnions 13—13 of the guard member 12. The stock 9 of each ear is preferably pressed outward into substantially a semi-spherical form on its outer surface, as illustrated in Fig. 1, which form serves to stiffen, strengthen and support the ends 20—20 of the hook shape portion of the ears 6—6, said hook effect being obtained by slotting the ears as at 10. When it is desired to open the mouth of the slot 10 in the keeper for the reception of the pointed end of the pin stem the handle 14 of the guard is carried over back against the stop 16 on the keeper in the position illustrated in Fig. 2.

In order to effectually secure the end of the pin stem that has been inserted in the keeper from being inadvertently removed therefrom, the handle 14 of the guard member is carried up and over until the edge 17 rests against the stock 18 on the front side of the base 7 of the keeper as illustrated in Fig. 3. In this position it will be noted that the slot 15 in the guard member extends straight upward or outward from the base forming the recess 11 at its end, into which the pin tongue 1 rises under its spring tension, in which position this pin-tongue forms a natural lock to retain the guard in its closed position, requiring extra pressure on the guard member to force the pin-tongue out of the recess 11.

The device, owing to its especial construction, is extremely strong and durable even when formed of very light material. It is locked or retained in its closed position by the natural or normal action of the pin-tongue and owing to its smooth outer contour it is handsome and attractive in appearance.

I claim:

1. A safety catch comprising a keeper

having a pair of side ears formed integral with and bent up from a common base portion, said ears being provided with a radial 55 slot extending from its margin inward, and a guard member rotatably connected with said ears and also having a radial slot extending from its margin inward, the outer portions of said slots being adapted to register to admit the pin tongue thereinto, one of said slots extending to the axial center of the catch and the other extending to and beyond said center whereby the pin-tongue co-acts with said ear and guard member to 60 lock the latter when the same is rotated to carry its slot out of register with the slot of the ear.

2. In a safety catch, a keeper having a pair of side ears provided with coinciding 70 radial slots, and cup-shaped recesses, and a guard member having trunnions mounted in said recesses, said guard member being also provided with a radial slot adapted to coincide with the first mentioned slots, the 75 slots of said ears and guard member leading in from the margins of the respective parts to the centers thereof, the slots in said ears being offset at their inner ends.

3. A pin having a safety catch, a pin-tongue in said pin having its free end under spring tension when in said catch, said catch comprising a keeper constructed of a pair of side ears each provided with a cup-shaped recess to form a bearing, a guard 85 member having a pair of trunnions mounted in the recesses, said keeper being provided with an angular slot, said guard being provided with a radial slot, a portion of each of said slots being adapted to register to receive the pin-tongue, said guard adapted to be rotated to move its slot out of line with a portion of that in said keeper and into line with another portion of said latter slot whereby the pin-tongue secured therein is 90 permitted to move outward and lock the guard in its closed position.

In testimony whereof I affix my signature in presence of two witnesses.

EUGENE MOREHOUSE.
